UNITED STATES PATENT OFFICE.

EMIL HAAGA, OF CHEMNITZ, GERMANY.

CIRCULAR-KNITTING MACHINE.

1,206,217.

Specification of Letters Patent. Patented Nov. 28, 1916.

Application filed April 8, 1912, Serial No. 689,423. Renewed October 17, 1916. Serial No. 126,203.

To all whom it may concern:

Be it known that I, EMIL HAAGA, a subject of the King of Saxony, residing at Chemnitz, in the Kingdom of Saxony, Germany, have invented certain new and useful Improvements in Circular-Knitting Machines, of which the following is a specification.

This invention relates to improvements in circular knitting machines whereby the sinkers are guided more accurately than is possible with the circular knitting machines of known construction.

The accompanying drawing illustrates the device, in which—

Figure 1, shows a side elevation of the device partly in section and Fig. 2 is a plan view of a horizontal section of the device as shown in Fig. 1.

20 The various parts of the device are referred to by alphabetical characters, similar characters denoting corresponding parts in the several views.

The letter α designates the axis around which the revoluble parts of the machine revolve. The parts a , b and c , are rings, which, when the machine is in operation, revolve around this axis α . This axis therefore is the center of all the revolving members. The sinkers d , are provided for sinking the thread in a zig-zag course the thread being threaded in the needles e . This sinking is effected by the action of a sinker cam g , upon the head f , of the sinkers d .

35 The novel feature of this invention consists in the arrangement by which the head f , of the sinkers d , reciprocates in slots 1, 2 and 3, which are provided in the three rings a , b and c . The two rings a , b , which 40 have the guide slots, would be sufficient to insure the proper guiding of the sinker heads f . The third ring c , merely serves for connecting the two other rings a and b , the one with the other.

45 The slots 3, in the ring c , are radial and directed toward the axis α . The heads of the sinkers d have the curved parts 4, and 5 at each side so that the sinkers not only reciprocate in the slots 1, 2 and 3, but also 50 execute the necessary oscillating motions. The sinker ring h , serves for regulating the vertical reciprocating motion of the sinkers d . The sinker ring h is arranged below the sinker guides 1, 2, 3.

In Fig. 1, the sinkers are shown in two 55 positions, viz: in full lines d , and in dotted lines d' . The sinkers swing to and fro, between these two positions. When they are in the position d' they touch the outer periphery of the ring m . At a certain portion 60 of this periphery, a cam i is provided. The ring m , with the needles e and the sinkers d , rotate around the axis α , but the cam i , remains at a stand still in its position. For this reason the sinkers d must, each time 65 they pass by the cam i , swing outwardly upon the oblique surface. The sinker ring h , is formed in such a way that it will force the sinkers d , back into the position indicated by the dotted lines as soon as the 70 sinkers have passed the cam i . The sinker cam is shown at g .

Having now described the invention what I claim is,

1. An improved guiding device for the 75 sinkers of circular knitting machines comprising two concentric rings a and b , forming a vertical slot, a third concentric ring c , having radial slots therein and connecting the two rings a and b , a head on each沉器, 80 the sides of each沉器 head having portions sliding in the vertical guide slots, so that each沉器 head is accurately guided and the sinkers can oscillate in said radial slots when reciprocating, the sinker ring h 85 being mounted below the guides for the沉器 heads.

2. An improved guiding device for the sinkers of circular knitting machines, comprising in combination two concentric rings 90 forming a vertical slot, a third concentric ring having radial slots and serving for connecting the two concentric rings a and b , curved extensions at either side of the head of the sinkers sliding in the vertical 95 guide slot so that the沉器 head is securely guided and the sinkers can oscillate in the said radial slots when reciprocating, substantially as described and shown and for the purpose set forth.

In witness whereof I have hereunto set my hand in the presence of two witnesses.

EMIL HAAGA. [L.S.]
